PRESSED STEEL COVER FOR DOMES

Filed July 23, 1932

Fig. 1.

Fig. 2.

A technical line drawing of a belt. The belt features a central rectangular panel with a horizontal slot in the middle. Various parts are labeled with numbers: 18, 22, 23, 19, 13, 14, 21, 25, 50, 49, 17, 20, 15, 12, 11, and 10. The drawing shows the belt's construction with a top layer, a middle layer, and a bottom layer.

PRESSED STEEL COVER FOR DOMES

Andrew A. Kramer, Kansas City, Mo.

Application July 23, 1932, Serial No. 624,216

6 Claims. (Cl. 220—24)

My invention relates to sheet metal covers for dome-like members, and more particularly to a pressed steel cover for domes. This application contains matter divided out from my co-pending application Serial No. 340,109, filed February 15, 1929, and is a continuation in part of said application.

It is a purpose of my invention to provide a new and improved cover member for a dome or expansion chamber, said cover member being made out of heavy sheet metal and being of unitary seamless construction, being die-shaped or pressed out of a sheet of heavy gauge steel.

It is a particular purpose of my invention to provide a pressed steel cover member having a depending annular flange extending perpendicularly to the body portion of the cover member and externally threaded to engage with a thread on the member to which said cover is attached, said cover member further being provided with a peripheral flange extending laterally therefrom to clamp a gasket between the flange and the member to which the cover is attached.

It is a further purpose of my invention to provide a cover member of the above mentioned character with a filler opening therein that is closed by a plug or similar closure member. Preferably, this plug is threaded in place and the opening is surrounded by a depending flange, which is internally threaded to cooperate with the threads on the plug. The cover member is further, preferably, provided with projections that are adapted to be engaged by a bar-like member for turning the cover member to remove the same or to screw the same into closing position. Said projections may be either in the form of stamped out portions or in the form of headed members extending through openings in, and riveted to the body portion of the cover member. In either arrangement the projections provide a pair of substantially diametrically opposite lugs projecting from the top, or outer surface, of the cover member.

It is a specific purpose of my invention to provide a pressed steel cover member having a body portion provided with a doubled back peripheral edge portion providing a lateral flange thereon and terminating in a threaded portion extending perpendicularly to said doubled peripheral edge portion, but spaced inwardly from the periphery of the cover member to provide a clamping portion on the cover member outwardly of the perpendicular flange portion, and to provide said cover member with an internally threaded depending flange around a central opening therein.

Other objects and advantages of my invention will appear as the description of the drawing proceeds. I desire to have it understood, however, that I do not intend to limit myself to the particular details shown or described, except as defined in the claims.

In the drawing:

Fig. 1 is a top plan view of one form of my improved pressed steel cover member, mounted on a dome.

Fig. 2 is a vertical sectional view thereof, taken on the line 2—2 of Fig. 1, also showing a fragment of a dome, with which said cover member is associated, in vertical section.

Fig. 3 is a view similar to Fig. 2 of a slightly different form of cover member in position on a dome, portions of said cover and of the plug being in elevation.

Fig. 4 is a fragmentary sectional view taken on the line 4—4 of Fig. 3.

Fig. 5 is a top plan view of a cover member, showing a closure member therefor held in closing position by a lever clamp.

Fig. 6 is a fragmentary side elevation of the cover member shown in Fig. 5, and

Fig. 7 is a view similar to Fig. 2, of the cover member shown in Figs. 5 and 6, the plug being partly in elevation.

Referring in detail to the drawing, in Figs. 1 and 2, one form of my improved cover member is shown as being applied to a dome 10, having a top wall 11 provided with an opening therein surrounded by a depending internally threaded flange 12. My improved cover member 13 is provided with a doubled back peripheral portion 14, providing a lateral flange thereon, and with a down-turned, or depending, externally threaded flange 15 thereon, said flange 15 being a perpendicular extension of the lower ply of the doubled portion 14 of said dome 13. The threads on the externally threaded portion 15 engage with threads on the internally threaded flange 12. The cover member is made out of heavy gauge sheet metal by a die-shaping process, and has the projections 16 struck out of the same so as to provide a pair of lugs or projections on the body portion of the cover 13, which are arranged substantially diametrically opposite each other for engagement by a bar or similar member for turning the cover member to tighten the same on the dome-like member or other member upon which the same may be mounted, or to unscrew the same.

Said cover member 13 is further provided with a down-turned inwardly extending internally

threaded flange 17, surrounding a central opening therein and extending substantially perpendicularly to the body portion of the cover member 13. A filler plug or closure member 18 is provided for the opening in the cover member 13, and has a lateral peripheral flange 19 overlapping the body portion of the cover member 13, and a perpendicularly extending annular flange 20, which is externally threaded and engages with the internally threaded flange 17 on the cover member 13. The cover member 13 serves as a man-hole cover or similar closure, and the closure member 18 serves as a filler plug, either the cover member 13 or the closure member 18 being removable, as desired. A compressible gasket 21 is clamped between the doubled portion 14 of the cover member and the dome-like member, and a gasket 22 is clamped between the flange 19 on the filler plug 18 and the cover member 13.

The cover member described in detail above is the cover member shown and described in my application Serial No. 340,109, filed February 15, 1929, which application has been limited to the structure of the dome-like member itself, of which this application is a continuation in part, insofar as the subject matter relating to the cover is concerned.

In Figs. 3 and 4 a slightly modified form of cover member is shown, which is applied to a dome-like member, and inasmuch as the particular form of dome-like member with which the cover member is associated is not a part of this invention, the same form of dome-like member is shown in Figs. 3 and 4 as in Figs. 1 and 2, and the same reference numerals are applied thereto. The cover member 13' shown in Figs. 3 and 4, is provided with a doubled peripheral edge portion 14 just as in the form shown in Figs. 1 and 2, and for the same purpose, the gasket 21 being provided between the flange formed by the member 14 and the upper surface of the dome-like member, while the depending externally threaded flange portion 15 is also the same as shown in Figs. 1 and 2, and cooperates with the internally threaded flange 12 on the dome-like member in the same way. The size of the filler opening and the type of plug member provided therefor, may, of course, vary, and a somewhat larger filler opening is shown in Figs. 3 and 4, having the depending internally threaded flange 17 surrounding the same, with which the externally threaded flange 20 on the plug member 18' cooperates, the plug member 18' being provided with a flange 19 for clamping the gasket 22 between the same and the cover member 13', and having handles 41 thereon, to facilitate turning thereof and being provided with venting means 48, which are not part of this invention, and the internal structure of which is accordingly not shown herein.

The cover member 13' is provided with an offset at 23 where the body portion thereof joins with the doubled flange portion 14, this offset providing for additional stiffness in the cover member 13' at the lateral peripheral flange thereon. In order to prevent loss of the plug member 18' the inner surface of the cover member may be provided with a U-shaped staple-like member 24, which may be welded or otherwise secured thereto, and the plug 18' with a perforated ear or lug 25, and a flexible member, such as a chain 26, may be provided between the members 24 and 25 for securing the plug 18' to the cover member so as to prevent loss thereof, said chain being connected with the plug by means of a swivel 49 and ring 50 to prevent turning of said plug without

interference by said chain. The cover member 13', instead of having the outwardly struck portions 16 thereon to provide the lugs by which the same may be turned with a bar-like member, is provided with openings therein that are substantially diametrically opposite each other, through which the reduced portions 27 of the headed members 28 extend, the enlarged portions or head portions 28 forming projections or lugs, for engagement by a bar-like member, on the outer surface or top surface of the cover member 13'. The headed members forming said lugs are secured in position by upsetting or riveting the reduced end portions 27 thereof on the inner face of the body portion of the cover, as shown at 29.

Instead of providing a screw-threaded closure member for the opening in the cover member, a closure that is held in position by a clamping bar, may be provided. A cover member with such a closure for the filler plug opening is shown in Figs. 5, 6 and 7, the cover member 13'' shown in Figs. 5, 6 and 7 being the same precisely as the cover member shown in Figs. 3 and 4 except that the flange 17'' is unthreaded, and except for the fact that a pair of ears or brackets are provided on the top of the cover member 13'', the bifurcated upstanding ear 30 being provided for pivotally mounting the clamping bar 31 thereon, and the bracket 32 being provided, which has a pivoted link 33 thereon having an opening 34 therein for receiving the end of the clamping bar 31. The clamping bar 31 is provided with a seat at 35 for a cam 36 provided on the end of a clamping lever 37, which is pivoted on the link 33. The central portion of the clamping bar 31 is provided with an enlargement 38 having pivot ears 39 thereon, upon which the plug member 40 is pivotally mounted, the plug member having a peripheral flange 41 thereon for clamping the gasket 42 against the outer face of the cover 13'', and having an annular guide flange 43 thereon for centering the plug relative to the opening in the cover member. The lever is provided with an adjustable pivotal mounting at 44 so that movement of the clamping member 37 to clamping position will securely seat the plug on the cover member in liquid tight relation thereto. The cover member 13'' is made with the same dies as the cover member 13', the flange 17'' being left unthreaded and the brackets 30 and 32 being welded to the outer or upper surface thereof. The plug 40 is vented in a similar manner to the plug 18'.

What I claim is:—

1. A seamless sheet metal cover member of the character described having a body portion provided with a doubled peripheral portion providing a laterally extending integral flange thereon, said doubled portion terminating in an annular portion spaced inwardly from the periphery of said cover portion and providing an integral flange extending perpendicularly to said doubled portion, said body portion having an opening therein and a closure for said opening.

2. A seamless sheet metal cover member of the character described having a body portion provided with a doubled peripheral portion providing a laterally extending integral flange thereon, said doubled portion terminating in an annular portion spaced inwardly from the periphery of said cover portion and providing an integral flange extending perpendicularly to said doubled portion, said body portion having an opening

therein, an integral flange surrounding said opening and a closure for said opening.

3. A seamless sheet metal cover member of the character described having a body portion provided with a doubled peripheral portion providing a laterally extending integral flange thereon, said doubled portion terminating in an annular portion providing an externally threaded integral flange spaced inwardly from the periphery of said cover member extending perpendicularly to said body portion, said body portion having an opening therein, an internally threaded integral flange extending from the inner face of said cover at said opening and a threaded closure plug engaging said internally threaded flange, said body portion having a pair of headed members riveted in openings therein to provide a pair of opposed lugs on the outer face thereof.
4. A seamless sheet metal cover member of the character described having a body portion provided with a doubled peripheral portion providing a laterally extending integral flange thereon, said doubled portion terminating in an annular portion spaced inwardly from the periphery of said cover portion and providing an integral flange extending perpendicularly to said doubled portion, said body portion having an opening therein and a closure for said opening, said body portion having an annular offset therein adjacent said doubled peripheral portion substantially opposite said perpendicular flange.
5. A seamless sheet metal cover member of the character described having a body portion pro-

vided with a doubled peripheral portion providing a laterally extending integral flange thereon, said doubled portion terminating in an annular portion providing an externally threaded integral flange spaced inwardly from the periphery of said cover member extending perpendicularly to said body portion, said body portion having an opening therein, an internally threaded integral flange extending from the inner face of said cover at said opening and a threaded closure plug engaging said internally threaded flange, said body portion having a pair of headed members riveted in openings therein to provide a pair of opposed lugs on the outer face thereof.

6. The combination with a domelike member having an opening therein, said member having an internally threaded flange surrounding said opening and having a wide annular seat formed by a top wide, flat, annular face on said wall portion adjacent said opening, of closure means for said opening comprising a sheet metal cover member having a body portion provided with a lateral, flat, wide, integral flange and an externally threaded integral flange continuous with said lateral flange spaced inwardly from the periphery of said body portion and perpendicularly to said lateral flange engaging said internally threaded flange, and a compressible gasket surrounding said externally threaded flange and mounted between said lateral flange and said seat.

ANDREW A. KRAMER.
